UNITED STATES PATENT OFFICE.

ISAIAH E. HINDMAN, OF BELLEVUE, PENNSYLVANIA, ASSIGNOR TO THE DUFF MANUFACTURING COMPANY, OF PITTSBURGH, PENNSYLVANIA, A CORPORATION OF PENNSYLVANIA.

LIFTING-JACK.

1,816,575.

Specification of Letters Patent. Patented Sept. 23, 1919.

Application filed February 20, 1918. Serial No. 213,324.

To all whom it may concern:

Be it known that I, ISAIAH E. HINDMAN, residing at Bellevue, in the county of Allegheny and State of Pennsylvania, have invented a new and useful Improvement in Lifting-Jacks, of which the following is a full, clear, and exact description, reference being had to the accompanying drawings, forming part of this specification, in

10 which—

Figure 1 is a side elevation with a part of the casing removed and showing a portion of a jack embodying my invention; and

Fig. 2 is a similar view with the parts in 15 a different position.

My invention has relation to lifting jacks, and more particularly to single-acting jacks which may be operated either to raise or lower the load. The invention is more 20 specifically designed as an improvement upon the lifting jack described and claimed in the patent of W. McH. Alston and myself, dated December 28, 1915, No. 1,165,380.

The object of the present invention is to 25 simplify and improve the mechanism for controlling the action of the pawls.

Referring to the accompanying drawings, in which I have illustrated a preferred embodiment of the invention and which will 30 now be described, the numeral 2 designates the usual lifting bar mounted for vertical movement in the frame 3, and having ratchet or rack teeth 4 at one edge. 5 designates the usual actuating lever which is trunnioned in the frame, as indicated at 6. 7 designates the upper pawl which is mounted on a pivot 8, carried by the heel of the lever 5; and 9 is the lower pawl which is pivoted to the frame at 10.

40 As thus far described, the parts may be similar in character to the corresponding parts in said patent.

The numeral 11 designates an angle lever which is pivoted at its angle portion to the 45 frame, as indicated at 12. The forwardly projecting arm of this lever has therein a curved slot 13, which is engaged by a stud 14 on the shorter arm of a reversing lever 15, whose other arm projects through a slot 50 16 in the casing in position to be actuated.

The numeral 17 designates a cam member which is pivoted at 18 to the other and upwardly extending arm of the lever 11. The member 17 is shown as being of 55 general K-shape, its concave side facing the

lever 5 and having the upper cam portion 19 and the lower cam portion 19^a. The upper pawl 7 is connected to the upper rear corner portion of the member 17 by a helical spring 20, and the lower pawl 9 is similarly 60 connected by a spring 21, with the lower rear corner portion of said member 17.

The numeral 22 designates a rearwardly projecting arm which is rigidly secured to one of the trunnions 6, and which is adapted 65 to coöperate with the cam portions of the member 17 in the manner hereinafter described.

In Fig. 1, the parts are shown as being in position for the raising of the load with the 70 actuating lever 5 in its upward position and ready for the commencement of its down or working stroke. At this time, both springs 20 and 21 are under some tension. As the lever 5 is moved downwardly, the pawl 7 75 raises the bar 2 and pawl 9 is idle. As the lever 5 approaches the limit of its down stroke, the end of the arm 22 engages the upper cam portion 19 of the member 17 and rocks said member on the center 18 to the position shown in dotted lines in said figure, thereby increasing the tension on the spring 20 and decreasing the tension on the spring 21. On the upstroke of the lever 5, the pawl 7 is therefore held by its spring against the 80 rack teeth while it moves downwardly over said teeth to new engaging position. During the further downward movement of the lever 5, the arm 22 will ride out of engagement with the upper cam portion 19 of the member 17, and thereafter into engagement with the lower cam portion 19^a, thereby 85 again shifting the parts into the position shown in full lines in Fig. 1, in which the tension on the upper spring 20 is decreased 90 and the tension on the lower spring 21 is increased. In the positions which the parts occupy during the raising operations of the jack, the shifting movements of the members 17 have comparatively little effect upon 95 the springs 20 and 21; and these springs are at all times under some tension or at least are not compressed beyond their neutral positions. In fact, in so far as the raising action is concerned, the member 17 100 may be made so as to have practically no action upon the pawls.

In order to adapt the jack for use for lowering a load, the lever 15 is shifted to the position shown in Fig. 2. This swings 105

the angle lever 11 from the position shown in Fig. 1 to the position shown in Fig. 2, thereby moving its upwardly extending arm forwardly and shifting the member 17 bodily forward. The effect of this movement is to place the upper spring 20 under compression (when the parts are in the position shown in full lines in Fig. 2) and to put the lower spring 21 under considerably increased tension. Therefore, the upper pawl 7 will in this position of the parts be forced entirely out of engagement with the rack teeth, while the lower pawl 9 will be drawn firmly into engagement with such teeth. As the lever 5 moves downwardly, the end of the arm 22 contacts with the upper cam portion 18 of the member 17, and said member is thereby shifted on the center 18, so as to place the upper spring 20 in tension and the lower spring 21 in compression. The upper pawl 7 (which has now been lifted to a new engaging position) is now pulled into engagement with the rack teeth, while the engagement of the lower pawl will be released. On the upstroke of the lever 5, the load moves down with the pawl 7 until near the limit of the stroke. The arm 22 then shifts the member 17 to bring the parts to the position shown in full lines in Fig. 2, with the pawl 7 free and the pawl 9 holding the load.

The advantages of my invention result from the provision of the shiftable angle lever 11 and cam member 17, or their equivalents. The provision of these parts enables the pawl springs to be at all times maintained under the necessary tension while lifting the load, but permits them to be alternately placed in tension and compression while lowering the load. The member 22 or its equivalent carried by the actuating lever provides for positively insuring the change in the nature of the spring action as the actuating lever approaches the limit of its strokes.

I do not desire to limit myself to the particular construction and arrangement of the parts as herein shown and described, since it will be obvious that various changes may be made therein within the spirit and scope of the appended claims.

I claim:

1. In a lifting jack, the combination of a

lifting bar, a frame, an actuating lever pivoted to the frame, upper and lower pawls, 55 one of said pawls being pivoted to the actuating lever while the other being connected to the frame, a cam support pivoted to the frame, a cam member pivotally mounted on the cam support, a spring connecting each pawl with said cam member, a member carried by the actuating lever and adapted to engage the cam member to reverse the action of the springs, and means for bodily shifting the cam support to bodily shift the 65 cam member to reverse the operation of the jack, substantially as described.

2. In a lifting jack, the combination of a lifting bar, a frame, an actuating member pivotally connected to the frame, a pawl pivoted to the actuating member, a pawl pivoted to the frame, an angle lever pivotally connected to the frame, a cam member pivotally connected to one arm of the angle lever, a spring connecting the upper arm of 75 said cam member with one pawl, another spring connecting the lower arm of the cam member with the other pawl, a combined shifting and locking lever for the angle lever pivotally mounted on the frame, 80 and a hand lever connected to the locking member, substantially as described.

3. In a lifting jack, the combination of a lifting bar, a frame, an actuating member pivotally connected to the frame, an angle 85 lever pivoted to the frame, a cam member having upper and lower arms pivoted to the angle member, a pawl connected to the actuating lever, a pawl connected to the frame, a spring connecting one pawl with the upper arm of the cam member, a second spring connecting the lower arm of the cam member with the other pawl, a member carried by the actuating lever and adapted to alternately engage the upper and lower arms of 90 the cam member near the ends of the movement of said lever, a shifting member pivoted to the frame for shifting the angle member to reverse the action of the jack, 95 said shifting member and angle member having connecting means arranged to lock the angle member in either of its shifted positions, substantially as described.

In testimony whereof I have hereunto set my hand.

I. E. HINDMAN.
